UNITED STATES PATENT OFFICE.

JOHN H. WILLETT, OF CHICAGO, ILLINOIS.

ARCH-SUPPORT.

1,240,275.

Specification of Letters Patent. Patented Sept. 18, 1917.

Application filed December 29, 1916. Serial No. 139,616.

To all whom it may concern:

Be it known that I, JOHN H. WILLETT, a citizen of the United States, residing at Chicago, in the county of Cook and State of Illinois, have invented certain new and useful Improvements in Arch-Supports, of which the following is a specification.

This invention relates to an improvement in arch supports or instep props, and more particularly to a device of this character which is constructed to be fitted within a shoe to bear against the plantar surface of the foot and is adjustable to vary the distribution of the supporting pressure exerted upon the arch or instep.

An object of my invention resides in providing a support or prop including a more or less fixed supporting plate and a flexible covering, together with means by which the plate is adjustably mounted with respect to the flexible covering so that the plate can be set in varied relations with respect to the covering to bring the pressure to bear at different points beneath the metatarsal arch and with respect to the longitudinal arch.

A further object lies in so constructing the fastening means for the two members that adjustment can be made of the shaped member longitudinally of the covering member and also lateral adjustment can be accomplished to in this way give greater latitude of use due to the fact that it is not necessary to have a special support for each deformed condition but the arches of a single design can be adjusted to secure the proper corrective pressure for differing cases.

Yet another object is to provide the shaped member with a molded portion to be received against the anterior metatarsal arch and to be adjustable transversely within the shoe to distribute the weight of the wearer properly upon the foot and in this way aid in the strengthening of the arch and in a natural correction of the deformity.

With the above and other objects in view, my invention consists in certain novel features of construction and combinations of parts which will be hereinafter set forth in connection with the drawings and then more particularly pointed out in the claims.

In the drawings:—

Figure 1 is a view in bottom plan of an arch support constructed after the manner of my invention.

Fig. 2 is a view similar to Fig. 1 taken from the upper side of the arch support.

Fig. 3 is a longitudinal sectional view taken on the line 3—3 of Fig. 2.

A stiffening member 1 is shaped at the heel portion 2 thereof to fit and bear within a shoe against the sole thereof, is raised in an arch 3, and then terminates at its remaining end in a broadened out portion 4 adapted to be received against the sole portion of the shoe forward of the instep arch of the same. At its side, the plate or stiffening member 1 is widened out as at 5 and is bent up or otherwise molded or shaped to take the form of the side of the foot and the arch. This shaping of the arch 3 and the formation of the foot 5 provides a structure which will present a rise or arch on that portion of the sole of the shoe adjacent the metatarsal arch of the foot. A covering member 6, which is of a material which is used to conform to and mold over the lines of the stiffening member 1 is provided to cover over the entire stiffening member, and to give the proper smoothness to the completed arch support, it is preferable that this covering member 6 be made so that it will project at its marginal edges at all sides beyond the edge of the stiffening member 1. The widened out and flattened portion 4 of the stiffening member is bossed up as shown at 7, and it is a purpose that this bossed up portion shall present a rise on that portion of the arch structure which will fit beneath the anterior metatarsal arch of the foot.

The parts as described might be fitted together to be rigidly mounted one with respect to the other, and a very efficient support would be provided as the bossed up portion 7 fitting beneath the anterior metatarsal arch would brace up this part whereas the arched formation 3 of the stiffening member 1 would hold the arch raised to the proper degree, however, it is desirable that provision be made for the adjustment of the stiffening member 1 with respect to the covering member 6 so that the disposition of the bossed up portion 7 and also the relative mounting of the stiffening member as an entirety with respect to the covering member 6 can be varied. It will be understood that the covering member 6 will fit within the lines of the shoe and that consequently this member will determine the position occupied by the arch support in a shoe, in view of which fact the adjustment of the stiffening member 1 with respect to the covering mem-

ber 6 will vary the shape of the support as the same is presented to bear against the plantar surface of the foot. With this purpose in view, I provide at the heel end 2 of 5 the stiffening member 1, a slotted opening 8 which is disposed to lie in line with the longitudinal extent of the member 1. Adjacent the forward end of the stiffening member 1, but rearwardly of the bossed up portion 7, a 10 substantially crowfoot shaped slotted opening 9 is formed. Screws 10 and 11 are extended through suitable openings provided in the covering member 6, and after being passed through the slotted openings 8 and 15 9, have the nuts 12 and 13 fitted thereon. It is of course to be understood that the screws 10 and 11 are so positioned that when the screw 10 occupies the rear end of the slot 8, the screw 11 will be in a like position in 20 the slotted opening 9.

In the use of the arch support, if the proper adjustment has been obtained, the arch supporting structure can be fitted within the shoe to be held in place by the covering member 6 and the stiffening member 1 will then hold the covering member 6 in such relation that the bearing of the same against the plantar surface of the foot will give proper support to the arch of the foot. As 30 has been stated, the covering member 6 will determine the position of the arch supporting structure within the shoe, and therefore adjustment of the stiffening member 1 with respect to the covering member 6 will accomplish variation of the configuration of the covering member 6 as presented for the bearing of the foot thereagainst. By loosening the screws 10 and 11, the stiffening plate or member 1 can be shifted to any of the various positions as shown in Fig. 1, to bring 40 the arch 3 and the bossed formation 7 rearwardly, to throw the forward end 4 of the stiffening member having the boss 7 formed therein through either side and to thus vary 45 the disposition of the supporting structure of the arch.

From the foregoing it will be seen that the stiffening member can be adjusted to a number of various positions with respect to the covering member to thus change the surface shape of the arch support, and that by tightening the screws 10 and 11 the stiffening member 1 can be locked and secured in the adjusted position with respect to the covering member 6. When the stiffening member 1 is adjusted forwardly and rearwardly, it will vary the bearing pressure exerted upon the metatarsal arch of the foot, and perhaps more particularly will this be true with respect to the anterior portion of the arch, and also it will be seen that by swinging the stiffening member 1 at its forward end to the one side or the other, to bring the screw 11 into the branched arms of the slotted 65 opening 9, the disposition of the bossed up

portion 7 will be varied and in consequence the foot will be raised at the one side or the other to better distribute the weight of the wearer for the obtention of the proper support of the foot.

While I have herein shown and described only one specific form of the structure, it will be understood that a number of changes and variations might be resorted to in the form and arrangement of the parts as well 70 as in the materials used in the construction of the arch support, and while it is perhaps preferable that the stiffening member 1 be of aluminum, German silver, or other like metal, and that the covering member 6 be of 75 leather, and hence I do not wish to be limited to the exact disclosure but only to such points as may be set forth in the claims.

I claim:

1. An arch support adapted to be fitted 85 within a shoe upon the sole thereof to thus be disposed to bear against the plantar surface of the foot, including a stiffening member shaped to fit the instep arch of the foot and having slotted openings formed there- 90 through near the ends, a covering member of a material which in use will conform to the shape of the stiffening member mounted over said stiffening member, and means passed through the covering member and 95 through the slotted openings of the stiffening member to secure the same together to be capable of adjustable movement through shifting of said means within the slotted openings.

2. An arch support including a stiffening member shaped to a form to fit the foot and having slotted openings provided at the forward and rear ends thereof, a covering member of a material which will conform 105 to the shape of the stiffening member made of a size to fit within a shoe and determine the position of mounting of the support, and screws passed through the slotted openings and through the covering member to hold 110 said members connected together but at the same time allowing movement of the stiffening member with respect to the covering member to vary the bearing and surface as presented by the covering member.

3. An arch support adapted to be fitted within a shoe upon the sole thereof to thus be disposed to bear against the plantar surface of the foot, including a covering member of a more or less flexible material which 115 in use will conform to the shape of the foot as supported, a stiffening member provided with an elongated slotted opening at one end and having a substantially crowfoot shaped slotted opening at the remaining 120 end, and means carried by the covering member fitted through the slotted opening to secure the stiffening member adjustably 125 in place thereon.

4. An arch support adapted to be fitted 130

within a shoe upon the sole thereof including a covering member of a more or less flexible material, a stiffening member arched up in its central portion and having 5 slotted openings provided at its ends, screws carried by the covering member fitted through the slotted openings of the stiffening member to mount the stiffening member adjustably upon the covering member, and 10 clamp nuts fitted on said screws to be tightened against the stiffening member to retain the same in adjusted positions.

5. An arch support adapted to be fitted within a shoe upon the sole thereof to thus 15 be disposed to bear against the plantar surface of the foot, including a covering member of a more or less flexible material which in use will conform to the shape of the foot as supported, a stiffening member arched 20 up in its central portion and at its forward end provided with a bossed up formation, said stiffening member provided with an elongated slotted opening at the heel end and at the toe end having a substantially 25 crowfoot shaped slotted opening, and clamp screws extending through the covering member and through the slotted openings of the stiffening member to thus permit adjustment of the relative positioning of the 30 stiffening member within the shoe and to vary the distribution of pressure as exerted by the arch supporting structure upon the

anterior metatarsal arch and the longitudinal arch of the foot.

6. An arch support adapted to be fitted 35 within a shoe upon the sole thereof including a covering member of a more or less flexible material shaped to substantially fit the sole of the shoe and position the support thereon, a stiffening member arched up in 40 the central portion thereof to take substantially the shape of the instep arch of a foot, said stiffening member provided with an elongated slotted opening at one end and at the remaining end having a substantially 45 crowfoot shaped slotted opening, screws carried by said covering member fitted through the openings of the stiffening member and adjustable therein to allow adjustment of the stiffening member to vary the 50 distribution of pressure as exerted by the arch supporting structure upon a foot, and clamp nuts fitted to said screws to be tightened against the stiffening member and to thus secure the same in the desired adjusted 55 relation with respect to the covering member.

In testimony whereof I affix my signature in presence of two witnesses.

JOHN H. WILLETT.
